Primary Examiner — Lauren R Calve

(74) Attorney, Agent, or Firm — JoAnn M. Seaton;
 Griffiths & Seaton PLLC(57) **CLAIM**

The ornamental design for a hanger, as shown and described.

DESCRIPTION

FIG. 1 is a front, top perspective view of a hanger showing a first embodiment of our new design;

FIG. 2 is a rear, top perspective view thereof;

FIG. 3 is a front view thereof;

FIG. 4 is rear view thereof;

FIG. 5 is left side view thereof;

FIG. 6 is a right side view thereof;

FIG. 7 is a top view thereof; and,

FIG. 8 is a bottom view thereof.

The features shown in broken lines are portions of the hanger forming no part of the claimed design. The features shown in long dash-short dash bolded broken lines indicate the bounds of the claimed design and otherwise form no part of the claimed design.

1 Claim, 4 Drawing Sheets# US D882,969 S
